UNITED STATES PATENT OFFICE

ALBERT MENDELSOHN, OF PAINESDALE, MICHIGAN

APPARATUS FOR LOADING BROKEN ROCK

Application filed October 17, 1932. Serial No. 638,205.

This invention relates to an apparatus for use in handling broken ore or rock in loading the same into buckets or skips to be hoisted out of a mine or shaft. In carrying this invention into effect a horizontal post is fixed at a suitable height to the walls of a mine shaft or drift, and on this horizontal post is mounted an inclined member affording a slideway up which the broken ore is drawn by a scraper and is delivered to a hinged "flop" pan, overlying an open-topped bucket or skip to be filled, and having at its bottom an opening registering with the top of said bucket. When the latter is filled the hinged pan may be raised out of the way to permit the bucket or skip to be lifted and replaced by an empty bucket or skip, and the hinged pan is then again dropped so as to overlie the empty bucket, all as will be hereinafter more fully set forth.

In the accompanying drawings Fig. 1 is a plan view of an apparatus constructed in accordance with the present invention; Fig. 2 is a side view showing the invention in operative relation to a pile of broken ore to be loaded; Figs. 3 and 4 are plan and side views, respectively, of the loading apparatus; Figs. 5 and 6 are detail views of the loading scraper. Fig. 7 is a detail view of a horizontal post or bar to be fixed to the walls of the drift or shaft and by which the loading apparatus is supported. Figs. 8 and 9 are detail views of the end heads of said post or bar.

Referring to the drawings, 12 denotes a tubular post or bar to be fixed to the side walls of a mine shaft at a suitable height above the top of a bucket to be loaded with broken ore. This post or bar is provided at its opposite ends with enlarged parts or heads 13 and 13^a having roughened or toothed outer surfaces for gripping engagement with the walls of the shaft. The head 13 is provided with a shank 13^b through which end the tubular bar extends a rivet 13^c by which said head is fixed to said bar. The head 13^a is swivelled on a rivet or stud 14^b integral with a block 14 provided with a screw-threaded shank 15 which meshes with an internally threaded sleeve 16 fixed in the tubular bar

12 with a shrunk fit. Fixed to the end of the bar 12 is a reinforcing collar 17, to keep the said bar from splitting, and fitting against the end of said bar 12 and the sleeve 17 is a jack nut 16^a integral with the internally threaded sleeve 16. The head 14 is provided with openings 14^c at right angles to each other and into which openings a suitable tool may be inserted for turning said head and its screw shank in the sleeve 16 to lengthen or shorten the bar 12, by virtue of the telescoping construction afforded by said screw shank 15 and said sleeve 16.

Fixed to the bar or post 12 is an outwardly flaring slide or guideway 18 which may be secured in working position on said bar or post by the clamping blocks 19 and 20 embracing said bar or post and which may be tightened and held in place by the nuts 21 on the bolts 22 passing through said blocks. When the said nuts 21 are loosened the slide or guideway 18 may be adjusted to vary its inclination or to shift it laterally on the said post or bar 12. The slide or guideway 18, which may be made of half-inch iron plate, is provided with side flanges 18^a and with a removable wear plate 18^b preferably of $\frac{1}{4}$ inch iron plate.

Mounted near the top of the slide or guideway 18 is a bar 23 on which is hinged a flop pan 24, said flop pan having side plates 25 embracing said bar 23. The pan 24 is constructed with a large opening 26 which, when said pan is in working position, will be in register with an open-topped bucket 27 when said bucket is to be loaded with ore. The pan 24 is preferably provided with handles 28 by which it may be lifted to the position denoted by dotted lines in Fig. 2 when the loaded bucket 27 is to be removed to be replaced by an empty bucket.

The loading operation will be performed by means of a heavily weighted scraper 29 which will engage a pile of broken ore as denoted in Fig. 2. Connected with said scraper is a pull rope 30 passing over a snatch block 31 and sheave 32 to a drum 33 mounted on a platform 34 above the apparatus described. Also connected with said scraper is a tail rope 35 passing over a snatch block 36

36 and the sheave 32 and thence to the drum 33. The double drum is driven by an engine controlled by an operator on the platform 24 which will be provided with an opening 5 through which the operator may watch the scraper.

In the operation of the invention the drum 33 is rotated in a proper direction, the scraper 29 engaging a pile of broken ore, will be 10 loaded with said ore as it is drawn forward; and when it reaches the guideway 18 the load of ore will be drawn up said guideway and be delivered to the pan 24 and thence to the bucket 27. The pan 24 is provided with arms 15 24* which rest on the top of the bucket 27 when said pan is in operative position. To prevent the scraper from catching on the lower end of said guideway said lower end is preferably turned down as denoted at 18°. 20 The scraper will then be drawn back to the pile of ore by the tail rope 35 on the reverse rotation of the drum 33, these operations being continued until the bucket is loaded. The pan 24 will then be raised to enable the 25 loaded bucket to be hoisted out of the mine.

When the ore within the path of the scraper has been removed the nuts 21 may be loosened and the scraper be adjusted laterally on the bar or post 12 to bring it into proper opera- 30 tive relation to the pile of ore to make a complete clean-up of all the broken rock or ore at the bottom of the shaft. By varying the inclination of the slide or guideway 18 its lower edge 18° may always rest on the broken 35 rock at the shaft bottom.

To get the broken ore or rock which lies under the bucket, skip or other receptacle and slideway into a position from which it can be scraped into the bucket or skip the 40 slideway and bar or post are removed from the shaft, ropes are then reversed on the scraper and the broken ore or rock is scraped from under the bucket or skip and piled up in the opposite end of the shaft. Then the 45 post and slideway are put in place, the pull ropes reversed back to normal, and the broken ore or rock scraped up the slideway.

The snatch blocks 31 and 36, over which the pull rope 30 and tail ropes 35 run, are 50 anchored by being connected by chains 38 with eye-bolts 39 which are wedged into the walls of the drift or shaft; or these eye-bolts may be fixed in any other suitable manner.

From the foregoing it will be understood 55 that broken ore may be rapidly and conveniently handled in loading same into buckets, by the mucking operation of the scraper, as above described.

Having thus described my invention I 60 claim and desire to secure by Letters Patent:—

1. An ore loading apparatus for mines or shafts comprising an extensible and contractible post or bar to be fixed to the sides of 65 a mine shaft or drift, an inclined guideway

or slide adjustably mounted on said bar or post, a hinged, open-bottomed receiving pan open to said guideway, a weighted scraper constructed to drag broken ore from a pile up said guideway to said pan for delivery 70 to an ore-receiving bucket or skip, and means for moving said scraper to and fro in a loading operation.

2. An ore loading apparatus for mines or shafts comprising an extensible and contractible post or bar to be fixed to the sides of a mine shaft or drift, an inclined guideway or slide adjustably mounted on said bar or post, a hinged, open-bottomed receiving pan open to said guideway, a weighted 75 scraper constructed to drag broken ore from a pile up said guideway to said pan for delivery 80 to an ore-receiving bucket or skip, and means for moving said scraper to and fro in a loading operation, said moving means for said scraper comprising a double drum, pull and tail ropes connected to said scraper, snatch blocks and sheaves over which said ropes run, and anchoring means 85 for said snatch blocks and sheaves. 90

In testimony whereof I affix my signature.

ALBERT MENDELSON.
